UNITED STATES PATENT OFFICE.

ROBERT PROMBERGER, OF ALLEGHENY, PENNSYLVANIA.

PENCIL.

No. 893,367.

Specification of Letters Patent. Patented July 14, 1908.

Application filed November 12, 1907. Serial No. 401,887.

To all whom it may concern:

Be it known that I, ROBERT PROMBERGER, a citizen of the United States, residing at Allegheny, in the county of Allegheny and State of Pennsylvania, have invented certain new and useful Improvements in Pencils, of which the following is a specification.

This invention comprehends certain new and useful improvements in lead pencils, and the invention aims to effect certain economies, hereinafter particularly pointed out, both as regards the consumer and manufacturer, the invention consisting in certain constructions and arrangements of the parts that I shall hereinafter fully describe and claim.

For a full understanding of the invention reference is to be had to the following description and accompanying drawing, in which:

20 Figure 1 is a side elevation of a pencil constructed in accordance with my invention, Fig. 2 is a longitudinal sectional view thereof, Fig. 3 is a similar view illustrating the pencil after it has been worn down; and Fig. 4 is a view similar to Fig. 1 but with the pencil given a turn of ninety degrees.

Corresponding and like parts are referred to in the following description and indicated in all the views of the drawing by the same reference characters.

In carrying out my invention I construct the pencil of two sections 1 and 2, one of these being formed of cedar or other more or less scarce and costly straight grained wood, and the other section, 2, being formed of a cheaper wood of any inferior grain and of any particular kind. The two sections 1 and 2 are joined together at their adjacent ends to form the complete pencil stock, preferably by providing the section 1 with a saddle 3 in which the correspondingly formed chisel or tapered end 4 of the section 2 fits, the two sections being permanently connected together in any desired way to form a rigid joint. The lead or crayon core 5, it is to be noted, lies entirely within the section 1 and terminates at its inner end at a point about midway of the length of the entire stock contiguous to the pointed end of the section 2. Manifestly, the section 1 may be made of two halves, as is common in pencil manufacture, for the purpose of accommodating the core 5. The section 2 may be either an integral structure or similarly formed of two mating halves.

From the foregoing description in connection with the accompanying drawing, it will be seen that I have provided an improved construction of pencil in which the lead extends only about half the length of the entire stock, my invention being based upon the knowledge of the well known fact that ordinary pencils are rarely used when they have been cut down to about one-half their original length, the stub portion being unhandy and being usually thrown away. By forming a pencil as above described, then, I effect an economy as regards the consumer, who would be likely to get two of these what might be termed half pencils for the price of one ordinary pencil with the lead extending entirely therethrough and with the entire stock formed of fine and straight grain wood, and the consumer would not, under such circumstances, pay for what is ordinarily unused, undesirable and unsightly and will get the same use from a pencil constructed in accordance with my invention owing to the fact above noted that the stubs are seldom used.

In addition to effecting economies to the consumer my invention will also effect economy to the manufacturer, who would incur no appreciably greater expense for two pencils constructed in accordance with my invention than for one pencil of the ordinary character, as those portions of the wood which are not utilized as pencil stock, could be used for forming the sections 2. As it is well known that the finer grained woods such as cedar, which is now almost universally used for the better class of pencils, are becoming scarcer, the supply will be manifestly conserved by my invention, as such wood would go twice as far in the manufacture of the pencil. This conservation of the supply is also apparent from the fact that such finely grained woods can be used of shorter lengths than is now possible, thus enabling the manufacturer to use logs and parts of wood that are not now available under the methods heretofore employed, owing to knots and other imperfections in the shingles or logs from which the shingles are cut to form the pencil stocks.

Having thus described the invention, what is claimed as new is:

1. As a new article of manufacture, the herein described pencil constructed of two longitudinally aligned sections, one of which

is of straight grain wood and the other of which is of relatively inferior grain, and a core mounted in the first named section.

2. As a new article of manufacture, the 5 herein described pencil, constructed of two longitudinally alined sections, of which one is formed with a saddle, and of which the other is formed with a chisel end fitting in said saddle, one of said sections being composed of straight grain wood and the other of wood of relatively inferior grain, and a core mounted in the straight grain section.

10 3. As a new article of manufacture, the herein described pencil constructed in two 15 longitudinally alined sections, one of which

is of straight grain wood and the other of relatively inferior grain, the section of straight grain wood being formed with a saddle, and the other with a chisel end fitting in said saddle, and a core in the straight 20 grain section, the inner end of the core terminating close to the pointed end of the other section.

In testimony whereof I affix my signature in presence of two witnesses.

ROBERT PROMBERGER. [L. s.]
